HAMMER MILL FOR STOCK FEED

Gerald D. Arnold, Wauwatosa, Wis.

Application April 7, 1941, Serial No. 387,125

3 Claims. (Cl. 241—60)

This invention relates to improvements in the art of preserving valuable elements of organic materials, the present application being a continuation in part of my pending application, same title, Serial No. 231,110, filed September 22, 1938, Patent No. 2,241,654.

An object of this invention resides in the provision of improved mechanism for comminuting organic material while simultaneously withdrawing heat therefrom preparatory to the storage thereof.

More specifically, it is my object to provide an improved hammermill or grinding mill, wherein herbaceous stock food or other material may be comminuted or ground, heat being extracted from the material both before, during and after the grinding operation.

Another object of my invention is to provide a hammermill with cooling means for extracting heat not only from the outer casing thereof, but also directly from the internal screen or grinding surface.

A further object of the invention is to generally improve and simplify the construction and operation of hammermills for one or more of the above purposes, with particular reference to improvements in apparatus wherein herbaceous stock food is ground and cooled preparatory to the storage thereof.

In the drawing:

Figure 1 is a view in perspective of one form of apparatus having the present invention incorporated therein.

Figure 2 represents in cross section an improved hammermill, such as is shown in Figure 1.

Figure 3 is a front elevation of the hammermill shown in Figure 2, with parts broken away to best illustrate the construction thereof.

Like parts are identified by the same reference characters throughout the several views.

Referring to Figure 1, the apparatus includes a feed pipe 10 through which material, such as alfalfa, is delivered into a hopper 11, preferably provided with a mechanically driven feeder, such, for example, as a screw conveyor or a rotary valve 12 which admits material along with a small amount of air into a hammermill 15. In the embodiment shown, pipe 10 is in sealing relation to hopper 11, whereby the only air admitted into the mill through the hopper is the air which is entrapped in the material being fed. After treatment in the hammermill, as later described, the material passes out through the discharge pipe 16, blower 17, and discharge pipe 18, into a centrifugal separator 19 in which the air is separated

therefrom preparatory to storage of the material.

A heat extracting device, such as a radiator 22, having inlet and outlet pipes 23 and 24, respectively, may be supplied with refrigerant for direct evaporative expansion or with chilling brine or other refrigerant, such as cold water, when a supply of such is available. Radiator 22 is placed in a housing 25 in the path of all the air admitted to hammermill 15. Housing 25 opens into the base 26 of the mill at a point opposite to the junction of pipe 16 with said base.

In the apparatus shown in Figure 1, the hammermill 15, with improved cooling means, is coupled in a preferred manner for simultaneous grinding and cooling of material such as alfalfa as it passes therethrough. As best shown in Figures 2 and 3, the hammermill includes a double walled casing 27 providing a cooling jacket 28. Jacket 27 encloses a hammer assembly 30 rotatable on shafts 31 and including a series of disks 32 and a series of rotary extending hammers 33, with their inner ends pivotally engaged between successive disks. The rotor assembly may be constructed in any well-known manner.

A grinding screen 35 is supported within the casing 37 adjacent the path of the outer ends of the hammers. Screen 35 is supported on conduits which are connected between opposite ends of the casing 27 in communication with jacket 28 and are designed to cool the screen without impairing its normal function.

A trough 38 is provided at the bottom of the casing within the base 26. Base 26 is provided with ports 40, one of said ports registering with housing 25, and the opposite port registering with conduit 16.

Incoming material passing through the pipe 10, hopper 11, metering device 12, and into casing 27 is ordinarily relatively free from air, especially if the material builds up in pipe 10. An insufficient supply of air prevents proper distribution of material during the grinding operation. Hence an air inlet conduit 41, leading into the upper portion of casing 27, is provided to ensure an adequate air supply within the casing. Conduit 41 is connected to housing 25 to draw air from the interior thereof, after it has been cooled by radiator 22, whereby the cool air entering casing 27 through conduit 41 intermixes with material being fed through the metering device 12 to extract heat from the incoming material prior to its being acted upon by the hammer assembly 30. A control valve 42 in conduit 41 provides for selective regulation of the amount of air entering the

casing. Likewise, the amount of pre-cooled air, which is being drawn through trough 38 within base 26 by suction fan 17, is regulated by a valve 43 in the neck of housing 25.

During operation of the device, liquid coolant flows through inlet pipe 24, heat exchanger 22 which may be a radiator or an air washer, and outlet pipe 23, to absorb heat and to be recirculated. Part of the coolant from inlet pipe 24 flows through pipe 22 to enter casing jacket 28 of hammermill 15. The coolant circulates throughout the casing jacket and through conduits 36 which communicate therewith as at 42-42, Figure 3. The coolant leaves jacket 28 at the upper end thereof and flows through conductor 44 to the outlet conduit 23 of radiator 22. Atmospheric air is simultaneously being drawn by fan 17 through radiator 22, conduit 25, and in trough 38 to provide a refrigerated air stream flowing through the bottom portion of the mill, and in which material passing through screen 35 is entrained, to be removed from the mill and conveyed to separator 19 while further heat is simultaneously extracted therefrom.

Ordinarily a considerable amount of heat is generated within a hammermill during the grinding operation therein. Not only does the friction caused by grinding substantially raise the temperature of the grinding screen, but a substantial rise in screen temperature raises the temperature of material ground.

In the present device, the coolant flowing through screen supporting conduits 36 effectively withdraws the heat generated therein during the grinding operation not only to prevent any undue heating of the screen during grinding, but preferably to keep it at sub-atmospheric temperatures. Such a cooling operation is effective in preventing heat transfer from the screen to the material, and preferably results in heat extraction from the material during the grinding operation. As previously stated, the ground material passes through the screen 35, to be entrained and further cooled by the air stream flowing transversely through the bottom of the device along the walls of trough 38.

During the grinding operation the rotary assembly 30 causes the incoming material to be thrown about considerably within casing 27, during which time the material contacting the inner walls of jacket 28 is cooled by conductive heat transfer from the material to the walls, to be removed by the coolant flowing through jacket 28. The coolant flowing through jacket 28 substantially lowers the temperature of the air within the mill, and hence further reduction is obtained in the temperature of the material passing therethrough.

During use, the rotary assembly 30 acts as a suction fan to draw pre-cooled air through conduit 41 into the casing. It is important to admit only the right amount of air above the grind-

ing screen 35 in order to ensure proper action of the mill. If too much air is admitted, grinding is coarse and uneven, and if insufficient air is admitted the material is thrown about the interior of the casing with little effective grinding action. It is also important to be able to control the amount of air flowing through trough 40, the right amount being determined in accordance with the cooling capacity of radiator 22 as well as in respect to the rate at which the material is ground within the mill. The valve 46 is provided in pipe 22 for regulation of the amount of liquid coolant flowing through jacket 28 and screen supporting conduits 36.

I claim:

1. Apparatus for comminuting and cooling stock food, including a hammermill comprising a jacketed casing, a screen supported on conduits which communicate with the jacket of said casing, means rotatable within said casing for grinding and forcing material through said screen while simultaneously removing the heat therefrom, and means for removing said material while further lowering the temperature thereof, said means including means for pre-cooling an air stream and propelling said air stream transversely through the lower casing portion in which the material being removed is entrained.

2. Apparatus for grinding and extracting heat from stock feed and the like, including a grinding device comprising a jacketed casing, a feed inlet conduit leading into an upper portion thereof, means for directing a pre-cooled pneumatic stream transversely of a bottom portion of the casing, a grinding screen intermediate the inlet conduit and said stream directing means, a hammer assembly mounted for rotation adjacent the screen for the grinding of feed during passage through the device, means for conducting pre-cooled air into the casing intermediate the feed inlet and the grinding screen, conduit means contiguously engaging portions of said screen and connected between spaced portions of the jacket, means for circulating a coolant through the casing jacket and the conduit for the extraction of heat from material contacting the inner jacket walls and the screen.

3. Comminuting apparatus comprising a hammermill provided with a hammer assembly in combination with a foraminous screen and supports for said screen individually provided interiorly with conduits, together with means including connections for passing a refrigerating material through such conduits, whereby to absorb heat directly from said supports, said screen being in intimate heat conductive relation to said supports, being dependent thereon for support.

GERALD D. ARNOLD.
